FLUID REGULATING DEVICE

Filed June 2, 1943

UNITED STATES PATENT OFFICE

2,437,113

FLUID REGULATING DEVICE

Carl Oscar Josef Montelius, Stockholm, Sweden,
assignor to Aktiebolaget Imo-Industri, Stockholm, Sweden, a corporation of Sweden

Application June 2, 1943, Serial No. 489,344
In Sweden May 20, 1942

1 Claim. (Cl. 137—166)

1

The invention relates to a device for regulating the quantity of fluid in two circuits in a certain predetermined proportion relative to each other, and is specially adapted for workshop machinery, aeroplanes, etc., where two or more pistons or other apparatus shall be moved with predetermined speeds or to predetermined distances. It is previously known to make such a device containing a movable piston valve, which by its movement regulates the proportion of fluid flowing to two different passages.

More particularly, it is the object of my invention to provide a more accurate regulation of the flow than has been possible with the known devices and at the same time to make an apparatus which regulates not only the division of flow from a common piping into two different pipings, but also the return flow from these pipings in the opposite direction to the common piping. To these and other ends appearing hereinafter, my invention consists of the combination, location, construction and arrangement of the various parts, all as more fully explained in the following description and specifically pointed out in the claim.

In brief, these results are accomplished by the use of proportional metering or motor devices in combination with regulatory means for maintaining the pressure gradients across said devices substantially constant or preferably equal. If fluid is fed in parallel to a plurality of mechanically connected motors of positive type, the discharges from said motors should theoretically be in definite proportions to each other depending upon the relative displacements of the motors which will thus act as metering devices. However, any positive motor is such only to the degree to which leakage can be avoided. If the pressure gradients across two such positive motors are different, the actual flow through the respective motors will depart from the theoretical to an extent depending upon the differences in the pressure gradients. To produce definite proportioning through the motors, therefore, to eliminate the variable factor of leakage, it is necessary to maintain across them definite fixed pressure gradients either equal or constantly definitely related to each other. In accordance with the present invention, motors arranged as just indicated are associated with devices designed to maintain constant or equal pressure gradients despite differences of pressure which may arise in the system to which the fluid is being delivered. In brief, this is accomplished by causing selective throttling of the portions of fluid delivered from

the motors, the throttling being increased in the line from a motor at the discharge of which a lowered back pressure appears, thereby to increase such back pressure and secure, for example, its equality with the back pressure existing on the other motor or motors.

In the accompanying drawings, Fig. 1 is a sectional view of the device; Fig. 2 is a cross section to a larger scale along the line II—II, Fig. 1; Fig. 3 is a sectional view along the circle III in Fig. 2, this view being expanded in a plane; and Fig. 4 is a partial section along the line IV, Fig. 1.

Referring to the figures by characters of reference, 1 designates a common piping connected to the regulating device. The flow of fluid from this piping shall be divided into two portions to be transported from two different pipings 2 and 3, which portions should be exactly alike independent of the pressures in the pipings 2 and 3, or, on the other side, when the flow from these pipings which may be used to move hydraulic pistons or other apparatus, is reversed, the device is designed to regulate the return flow in a similar way.

25 In a common casing 4, there is made an axial bore 5 which is closed at the ends by means of plugs 6 and 7 screwed into the casing. In the bore 5, a piston 8 is arranged so that it fits exactly but may be easily moved. In another bore 9 which consists of three parallel, intersecting cylindrical bores, a set of three screws is fitted. These screws consist of a central power screw 10 and two idler screws 10a and 10b, one on each side, said idler screws cooperating in a known way with the power screw 10 so as to constitute two positively operating hydraulic motors driven by the flow of fluid. The power screw 10 has convex helical surfaces, while the cooperating idler screws 10a and 10b being made with concave helical surfaces. Each screw has two screw grooves and is divided in two portions comprising left-hand threads and right-hand threads, respectively, each of the said portions constituting a hydraulic motor. The motors so provided are of the type described in my prior Patents 1,698,802, dated January 15, 1929, 1,821,523, dated September 1, 1931, and 1,965,557, dated July 3, 1934, to which reference may be made for details of construction and operation.

40 50 The central portion 11 of the screws, which is not threaded, is through an opening 12 connected to the common piping 1. The ends 13 of the central screw 10 are limited in their movement by the plugs 14 and 15, which are screwed into the casing 4. From the chambers 16 and 17 at the

ends of the said screws, two bores 18 and 19, respectively, are cut to the chambers 20 and 21, respectively, located in the bore 5 on opposite sides of the piston 8.

The piston 8 has four axial bores or passages 22, 23, 24, 25 provided with non-return valves 26, 27, 28 and 29, respectively, said valves being constituted by spring-actuated balls (Fig. 3). The non-return valves are arranged in a manner such that the fluid in the passages 22 and 24 can flow upwardly only as viewed in Figs. 1 and 3, while in the passages 23 and 25 the fluid can flow downwardly only. The passage 23 is at its lower end closed by a plug 30. A similar plug 31 closes the upper end of the passage 24.

In the bore 5, there are provided two annular grooves 32 and 33, which through radial openings 34 and 35 are in open communication with the pipings 3 and 2, respectively. Each of the axial passages provided in the piston 8 communicates with a radial bore 36, 37, 38 and 39, respectively, by means of which said passages are connected to either of the grooves 32 or 33. As will be seen from Fig. 3, the bore 36 connects the passage 22 with the groove 32, and the bore 37 connects the passage 23 likewise with the groove 32, while the groove 33 communicates with the passages 24 and 25 by means of the bores 38 and 39, respectively. The radial bores 36, 37, 38 and 39 are arranged in a manner such that they in the intermediate position of the piston 8 shown in the drawing to half of their cross sectional area only directly communicate with the annular grooves 32 and 33. Consequently, at a displacement of the piston 8 in the one or other direction, the direct connection between two bores and the annular grooves will be increased, while at the same time the direct communication between the other two bores and the grooves will correspondingly be decreased. The movement of the piston in axial direction is limited by stop members 40 and 41.

The device described operates as follows.

The flow of fluid supplied through the common piping 1 will be divided into two portions imparting rotational movement to the set of screws 10, 10a, 10b. The portions of the fluid will pass from the chambers 16, 17 through the bores 18, 19 to the chambers 20 and 21, respectively. From the chamber 20, the fluid will pass through the non-return valve 27 in the passage 23 and through the radial bore 37 to the groove 32 and thence into the piping 3. In a similar way, the fluid from the chamber 21 will pass in the opposite direction through the non-return valve 28 provided in the passage 24 and through the bore 38 and the groove 33 into the piping 2. If now, for instance as a result of an additional resistance, the flow of fluid through the piping 3 is obstructed, and, consequently, an increased quantity of fluid tends to flow through the piping 2, a pressure difference will be built at the rotation of the set of screws, with the result that the pressure in the chamber 20 will be slightly increased above the pressure prevailing in the chamber 21. As a result thereof, the piston 8 will be moved downwardly as viewed in Fig. 1 so that the direct communication between the passage 24 and the bore 38 and groove 33 will be throttled until a state of equilibrium will be restored with respect to the flow of the fluid portions. In a similar manner, the quantity of fluid passing through the bore 37 will be throttled upon increase of the resistance to the flow in the piping 2.

If the fluid is flowing in the opposite direction, that is, from the separate pipings 2 and 3 to the

common piping 1, one of the fluid portions passes from the groove 33 through the bore 39, non-return valve 29 and passage 25 to the chamber 21, while the other portion of fluid passes from the groove 32 through the bore 36, non-return valve 26 and passage 22 to the chamber 20. From the chambers 20 and 21, the fluid portions then pass through the bores 18 and 19, respectively, to the screws and finally into the common piping 1. If it be assumed that the resistance in the piping 3 is increased for some reason or other, the pressure in the annular groove 32 will become lower than the pressure prevailing in the groove 33. The increased quantity of fluid which in this case passes from the groove 33 through the bore 39 and the passage 25 to the chamber 21 will result in that the pressure in the chamber 21 will be increased as compared with the pressure prevailing in the chamber 20. As a result thereof, the piston 8 will be moved upwardly as viewed in Figs. 1 and 3 so as to throttle the connection between the bore 39 and the groove 33, until the state of equilibrium is restored.

It will be understood that the invention is not limited to the embodiment shown and described by way of example only. If two or more devices of the kind described are used, it will be possible to divide a flow of fluid into more than two portions in certain predetermined proportions.

What I claim is:

A fluid regulating device comprising two positively operating hydraulic motors mechanically connected to each other, a common fluid piping connected to one end of each of said motors, a cylinder, a piston movable in said cylinder, a conduit for connecting the other end of one of said motors with one side of said piston, a conduit for connecting the other end of the other one of said motors with the other side of said piston, two separate fluid pipings connected to said cylinder, the areas of connections of said pipings to the cylinder being controlled by said piston, four passages in said piston, one pair of said passages communicating with one of said conduits and one of said separate pipings, the other pair of said passages communicating with the other one of said conduits and the other one of said separate pipings, a non-return valve in each of said passages, the non-return valves in each pair of passages being arranged to permit flow of fluid in opposite directions, and said piston being arranged to be displaced in said cylinder in response to differences in pressure on opposite sides of the piston to vary the cross-sectional area for the flow of fluid between said motors and said separate pipings to increase throttling action upon flow through the motor having a lowered pressure occurring at its discharge, whereby to reestablish the normal proportion of flow through said separate pipings.
